UNITED STATES PATENT OFFICE.

LOUIS F. HAGEMANN, OF NIAGARA FALLS, NEW YORK, ASSIGNOR TO AMERICAN SALES BOOK COMPANY, LIMITED, OF TORONTO, ONTARIO, CANADA, A CORPORATION OF ONTARIO.

AUTOGRAPHIC REGISTER.

Application filed February 5, 1917. Serial No. 146,681.

To all whom it may concern:

Be it known that I, LOUIS F. HAGEMANN, a citizen of the United States, residing at Niagara Falls, in the county of Niagara 5 and State of New York, have invented certain new and useful Improvements in Autographic Registers, of which the following is a full, clear, and exact description, such as will enable others skilled in the art 10 to which it appertains to make and use the same.

This invention relates to autographic registers, and more specifically to that type of machine in which a plurality of superposed 15 webs are fed over a support, suitable transfer material being disposed between the webs to enable a plurality of copies to be made.

An object of this invention is to enable 20 the registration of the sheets to be more accurately maintained relative to each other and to the machine, whereby the records will appear on the web, and the web will be severed in predetermined positions.

Other objects will be in part obvious and 25 in part pointed out hereinafter.

The invention accordingly consists in the features of construction, combinations of elements and arrangement of parts which will be exemplified in the construction hereinafter set forth, and the scope of the application of which will be indicated in the following claims.

The preferred embodiment of this invention 35 is illustrated in the accompanying drawings, wherein similar reference characters refer to similar parts throughout the several views, in which,—

Figure 1 is a side elevation;

Fig. 2 is a top plan view with the covers 40 removed;

Fig. 3 is a vertical section on the line III, III on Fig. 2;

Fig. 4 is a vertical section on the line IV, IV on Fig. 3;

Fig. 5 is a vertical section on the line V, V on Fig. 3, and

Figs. 6 and 7 are details.

The frame of the machine comprises side plates 1 attached at their lower edges to a base 2. Extending between the side plates 1 at one end of the machine or spaced guide rods 4, 5, and 6, and at the other end of the machine a tie rod 7, which rods may serve to brace the side plates together as 50 well as other purposes later to be described.

At the top of the side plates 1 is a support 8, which may conveniently be made of a separate piece resting in a cut-out portion 9 in the side plates, permitting ready removal of the support to give easy access to 60 the interior of the frame. This support may conveniently have at one side a trough 10 for holding a roll of carbon tissue, and may have at the other side a suitable means for retaining the carbon tissue, as a bar 11, 65 horizontally pivoted at one end, as at 12, of the support and having its other end retained in a notch 13. This bar may be provided at its pivot with a suitable thumb screw 14, and the free end of the bar may 70 be bevelled, as shown at 15, and the notch 13 may be shaped to engage the bevel.

Substantially central of the side plates 2 are vertical guides in which is adapted to 75 slide a reciprocating member 16, thus dividing the interior of the machine into two chambers, the one toward the rods 4, 5, and 6 being a roll-holding chamber and the one toward the rod 7 being a filing chamber.

The guides preferably comprise guide blocks 17, each having a longitudinal groove 18, each block being attached to the side wall by a screw 19, projecting through a horizontal slot 20 in the side plate, whereby adjustment of the position of the guide may 80 be made by adjusting the position of the screw in the slot. Suitable lugs 21 on the side plates are provided at the top and bottom of each block to hold the block in 85 place. Preferably two such blocks 17 are attached to each side plate with the grooves 18 in alignment, so that the reciprocating member 16 may slide in said grooves.

In the side plates 1 there is journaled 90 a crank arm 22 carrying on its outer end an operating handle 23, and having, in 95 the interior of the casing, an offset portion 24 for the purpose of operating the reciprocating member. The reciprocating member is provided on the face adjacent the arm 22 with suitable lugs 25 adapted to engage the offset portion of the crank arm, whereby on 100 operation of the handle 23, the reciprocating member will be moved vertically. Attached to the base of the machine, as by screws 26, is a spring 27 engaging a lug 28 on the reciprocating member 16 to draw the reciprocating member downwardly. Journaled in blocks 29 attached to the upper 105

side of each of the side plates 1, as by screws 30, is a web-feeding roller 31 in such position as to have its upper side substantially flushed with the upper side of the support 5 when the latter is in place. The roller 31 has preferably a roughened surface, and has one end of its shaft extend through one of the side plates for the reception of an operating crank 32, which may be threaded 10 thereon. To prevent rotation of this roller 31 in a reverse direction, a ratchet and pawl device is provided which may consist of ratchet teeth 33 cut into one end of the roller 31 and an engaging pawl 34 mounted on the side plate and held against the ratchet by a suitable spring. A second web-feeding roller 36 is journaled parallel to the first mentioned roller 31, and carries at its end a suitable pinion 37 adapted normally 15 to mesh with a similar pinion 38 on the roller 31, whereby the rollers are caused to rotate in opposite directions for the purpose of feeding the web between them. This roller 36 also has, preferably, a 20 roughened surface. In order, however, to enable the webs to be released, at will, from the grip of the feed rollers 31 and 36 to permit free adjustment of the web, the roller 36 is journaled in plates 39 which are 25 parallel to the blocks 29 and lie between the said blocks and the ends of the roller 31, whose shaft passes through a slotted orifice 40 in said plate, whereby the plate 39 may move vertically relative to the block 29 and 30 roller 31 carrying with it the roller 36.

In order, normally, to retain the roller 36 in engagement with the roller 31, the ends of the shafts of the roller 36 extend beyond the plates 39 in which said roller 40 is journaled, as shown at 41, through slots in the blocks 29, and threaded openings 42 are provided in said blocks above said extensions, in which are placed means for bearing down upon the ends of said shafts. 45 This may conveniently consist of a presser block 43 pressed downwardly by a spring 44 which is retained in place by a screw 45 threaded into the opening. For the purpose of enabling the roller 36 to be lifted out of engagement with the roller 31, there is journaled in the side plates 1 a shaft 46, carrying at one end an operating handle 47 and being provided, in position to engage the lower end of the plates 39 with cam surfaces, as shown at 48, whereby on rotation 50 of the shaft 46 the plates 39 are alternately raised and lowered, carrying with them the roller 36.

Extending between the side plates 1 and 60 attached thereto, as by screws 49, is a guide piece 50 comprising two side pieces 51 having extending therebetween two tie rods 52 and 53, one above the other. Also extending 65 between the side pieces, parallel to and between the tie rods 52 and 53, is a guide plate,

as 54, for directing certain of the webs upwardly out of the machine and certain other of the webs downwardly into the filing chamber. In order to cause a separation between the upper and lower webs, there is 70 provided in the guide piece 50, and with its upper and lower surfaces substantially flush with the upper and lower surfaces of the guide plate 54, a separating bar 55 forming slots for the reception of the webs, both 75 above and below it between it and the tie rods 52 and 53, as shown at 56 and 57. The mechanism for severing the web comprises a knife 58 attached to the reciprocating member 16, as by screws 59, and the upper 80 tie rod 52 which is so shaped as to form a cutter bar. The knife 58 preferably has one side, as 60, higher than the other to cause that side to engage the cutter bar before the 85 other.

In order to enable the knife to cooperate with the cutting bar without interference by the separator bar, means are provided for withdrawing the separating bar 55 backward beyond the edge of the cutter bar 52 at such time as the knife approaches the cutter bar. This is accomplished by slidably mounting the separating bar 55 for longitudinal movement in a slot in the guide piece 50. A separator bar operating shaft 62 is journaled 95 in the side pieces 51 of the guide piece 50, and carries at each end, as at 63, an operating pin adapted to engage slots 64 in the end of the separating bar, whereby on rotation of the shaft 62 the operating pins 63 will 100 cause movement of the separating bar 55 toward and away from the guide plate. A suitable spring on the shaft 62 tends to rotate the shaft 62 in a direction to hold the separating bar 55 in engagement with the 105 guide plate 54, and a cam arm 66 on the shaft 62, in position to be engaged by a finger 67 on the high side 60 of the knife 58 causes the rotation of the shaft 62 to withdraw the separating bar 55 away from the 110 guide plate 54 beyond the edge of the cutter bar 52. This permits the knife, as it rises, to engage the cutter bar to cut the web, and at the same time retains the separating bar 115 between the webs, whereby, when the knife is again lowered, it may return to a position in engagement with the guiding surface 54 to again cause the upper surface to be separated from the lower. This finger 67 also 120 serves to guide the high side of the knife over the edge of the cutter bar. The records from the lower web may be admitted loosely into the filing chamber for filing, but since it is desirable that they be retained in proper order, there is preferably mounted on the 125 reciprocating member 16 a filing member 68 which may conveniently consist of a head 69 having a stud 70 fitting into an orifice 71 in a boss 72 on the reciprocating member 16, and a filing pin 73 projecting upwardly 130

from said head, having attached to the upper end thereof a point 74, which may conveniently be screwed thereon. To permit of the removal of the papers filed on the pin

- 5 73, without losing the order thereof, an eye 75 may be provided in the pin through which a suitable string may be passed before the papers are removed from the filing pin 63, whereby the pin will act as a needle to 10 draw the string through the opening in the papers. A catch 76 engaging a notch 77 in the boss 72 normally holds the filing member in place. This catch may be operated by a spring 78. The filing member 68 is 15 conveniently steadied by making the head 69 of such shape as to fit flat against the reciprocating member 16 as the filing member is put in place.

In order to permit of relative adjustment 20 between the knife 58 and the cutter bar 52, the screws 49 of the guide piece 50 are preferably situated above the cutter bar 52, and engaging the lower end of one of the side pieces 50, is an adjusting member 79. This 25 comprises a block 80 pivoted to one of the side plates 2 by a screw 81, on which is slidably mounted between lugs 82 an arm 83 having at one end a finger 84 for engaging a slot in the bottom of the side pieces 30 51, having at the other end a lug 85 provided with a threaded orifice 86 and having at its center a longitudinal slot 87. The block 80 is provided with outstanding lugs 88 which engage a circumferential slot in 35 the head of an adjusting screw 89 which is adapted to screw into the orifice 86 of the lug 85. By this construction a rotation of the screw 87 will cause a longitudinal movement of the arm 83 causing a rotation of the guide piece 50 about its screws 49 as a pivot, whereby the cutter bar 52 is moved longitudinally of the machine, and toward and away from the path of the knife 58.

In order to retain the adjusting member 45 79 in engagement with the side piece 51, there is provided on the block 80 a spring 90 adapted to engage a lug 91 on the side plate 2 to urge the adjusting member upward.

50 In order to support that web which passes through the slot 57 below the separating bar, after the web has passed the separating bar into the filing chamber, there is provided on one of the side plates a guide spring 92. 55 Suitable slotted bosses, as 93, are provided on the inside of the side plates, inside the web roll holding chamber for receiving ends of the shafts 94 on which the rolls of the web are mounted. These shafts have at one 60 end a shoulder 95 against which is placed a washer 96 for bearing against the roll of web. A spring 97 bearing against one side plate 2 bears against the other end of the roll.

5 Machines of this character are customarily

used with webs having printed thereon suitable sales forms, and it is desirable to insure that the sales forms in the different webs shall be in register with each other as the webs are fed in order that the records shall 70 appear in the proper position on the sales forms on the lower webs. With a paper web, however, there is tendency of the webs to get out of register with each other, owing, perhaps, to the liability of the paper of the 75 webs to stretch or contract with different conditions of tension and atmosphere. For this reason, it is desirable to provide some means for adjusting the position of the webs relative to the machine and to each other. 80 This may be accomplished by providing physical alteration in the web, as, for example, a series of apertures, perforations, or of sets of perforations, bearing fixed relation to the forms printed on the web, and to provide means on the machine, as, for example, pins for engaging these alterations, whereby the position of the form may be adjusted by adjusting the position of the alterations.

The form of adjustment in the embodiment illustrated is as follows: To the top of the reciprocating member 16 is attached a bar 99 having controlling fingers, or pins, 100 projecting upwardly therefrom and reciprocal across the paths of the webs. When the reciprocating member is raised, the fingers 100 project upwardly above the normal level of the webs, the roller 31 being grooved, as at 101 and guide plate 54 and separating bar 55 being notched, as at 102, to afford a 95 passage for the pins. The pins 100 are of such distance apart, and in the present embodiment, are independent of the feed rollers, and in such position relative to the knife 58 and the apertures, or perforations 100 in the web are in such position relative to the printed form thereon, that when the webs are in position to be severed by the knife 58, the pins will be in position to enter the perforations in the web, the guide blocks 17 holding the pins from movement in the direction of feed of the webs, longitudinal movement, when in said apertures. Attached to the reciprocating member 16, as by screws 103, is a block 104 having an arm 105 adapted to engage the lower end of the plates 39 to raise the roller 36 from engagement with the roller 31 after the knife 58 and cutter bar 52 have severed the web, in order that the web may be free from the pull of the feeding mechanism, so that its position may be adjusted by the engagement of the pins 100 with the perforations in the web.

That portion of the machine which constitutes the filing chamber is provided with a suitable cover 106 which may conveniently be composed of two parts, one of which, as 107, is pivoted to the side plates 2 at the lower edge of the outer end thereof, and is 130

adapted to fold up against the end of the said side plates where it may be retained in plates by a lock 108 which may engage the rod 7, and the other of which, as 109, may be 5 hinged to the top of the part 107, and is adapted to lie horizontally on top of the side pieces 1. This horizontal portion of the cover may be provided with hooks 110 adapted to engage lugs 111 on side pieces 1 to 10 retain the horizontal portion in place when the vertical portion is held in position by the lock 108. The frame work of the machine and cover 94 thus form a closed filing chamber for the reception of the sheets 15 which are filed upon the filing member 68. The roll holding chamber may be provided with a cover 112, which may have, at one end, fingers 113, adapted to project below and catch under the end of the horizontal 20 portion 109 of the cover 106, and may be provided at the other end with a catch. The front of the machine may be closed by a door 115 adapted to slide in guide ways 116 in the side pieces 1, and pivoted on the door 25 115 is a spring-pressed catch 117 having one end adapted to engage a catch on the cover 112 and a lower end adapted to engage the edge of a notch 120 in the base 1. The operation of this latch may be controlled by a 30 pin 121. The cover 112 is provided with a suitable cut-away portion 122 adapted to expose the web above the support 8, so that a record may be made thereon, and the web will preferably have printed thereon a guide 35 mark which will be coincident with the edge of this cut-out portion 124 of the plate 112 when the perforations in the web are in alignment with the pins 100.

40 The operation of the machine is as follows:

Suitable rolls of web are mounted upon the shafts 94, and the springs 97 being placed upon the ends of the shaft, the shafts are held in place in the slotted bosses 93, 45 one roll being used for each copy which it is desired that the machine shall make. The web from each roll is then carried over its corresponding guide rod, as illustrated, the inner roll will be carried over the guide 50 rod 4; the central roll over the guide rod 5; and the outer roll over the guide rod 6. The support 8 may now be placed in position in the cut-outs 9, and the webs carried there-over.

55 The upper roller 36 will now be raised by turning the shaft 46 by means of the operating handle 47 until the cams 48 engage and raise the plates 39. This disengages the rolls from each other and permits the ready 60 insertion of the web therebetween. The lower web, that is, the web passing over the guide rod 4, will then be carried beneath the separating bar 55 and beneath the guide plate 54 to project through the slot 57 into 65 the filing chamber, and will be adjusted

until the perforations in the web are over the pins 100. The upper webs will then be carried over the support 8 and through the slot 56 above the separating bar 46 and guide surfaces 45. They also will be adjusted so that the perforations in the web are over the pins 100. As the webs are laid in place over the support 8, a carbon tissue from the roll in the trough 10 may be laid between them to cause the record on the upper sheet to be copied onto the lower.

70 The operating handle 47 will now be turned to lower the roller 36 to engage the webs, and the covers 106 and 112 will be placed in position on the machine. On pressing down the handle 23, the reciprocating member 16, carrying with it the knife 58, will be raised, whereby the finger 67, engaging the cam arm 66, will withdraw the separating bar 55 out of the way of the knife 58 and permit the knife to cut the web against the edge of the cutter bar 52; at the same time, the raising of the reciprocating member will cause the pins 100 to project through the openings in the web. When the severing of the web has been completed, the arms 105 will engage the plates 39 to raise the roller 36 from engagement 75 with the web. The web is now retained in place solely by the pins 100, and if any web has been fed slightly beyond the desired point, the normal tension in the web will permit a slight retrograde movement, because the diameter of the pins is less than the diameter of the perforations in the web, and thus all the webs are brought into such 80 position that the furthermost edge of the perforation appears against the far side of the pin, thus having its position adjusted 85 relative to the pins, and hence having the position of the forms printed on the webs adjusted relative to each other. Upon release of the handle 33, the spring 27 assisted by the weight of the reciprocating member 16 will cause the lowering of the reciprocating member to withdraw the pins and the knife, and to permit the return of the separating bar 55 which lies between the unsevered portions of the web to its 90 normal position in engagement with the guiding plate 54. Any record desired may now be made upon the first sheet of the top web, and thereafter the operating crank 95 may be turned, rotating both the roller 31 and the roller 36 to cause a simultaneous feed of all the webs through the machine. The separating bar 55 insures that those webs which have been originally inserted 100 in the slot 57 will all enter the filing chamber, and that those webs which have originally passed through the slot 58 will all pass out of the machine over the guide plate 54. The crank 32 is turned until the 105 next guide mark on the web indicates that 110 115 120 125 130

the proper length of feed has been made. Thereafter, upon operating the handle 23, the severing operation will take place as before described, and simultaneously therewith the pin 73 will pierce the first or severed sheet of the lower web, and on the lowering of the reciprocating member 16, this sheet will be carried down into the filing chamber, being prevented from sliding off the pin 73 by the point 74. This sheet is retained in the machine on the filing pin 73 until such time as it is desired to open the filing chamber. The sheets from the upper web which are cut simultaneously with the sheet from the lower web pass out of the machine, and are used for any desired purposes. Thus one copy of each sales record is kept in the machine.

Thus by the above described construction are accomplished, among others, the objects hereinbefore set forth, as well as others which will be obvious.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention, which, as a matter of language, might be said to fall therebetween.

Having described my invention, what I claim as new and desire to secure by Letters Patent is:

1. A device of the character described comprising, in combination, a support for a web, a member mounted on said support and fixed against longitudinal movement relative to the support for engaging a web to feed the same relative to the support, means to release the feeding means from engagement with the web to permit retrograde motion of the web, and means adapted to engage the web to limit the retrograde motion thereof when released and thereby retain a portion of the web in a predetermined position relative to the support.

2. A device of the character described comprising, in combination, a support for a web, means constantly urged towards said web to feed the same relative to the support, means for releasing the feeding means to permit retrograde motion of the web, and means adapted to engage the web to limit the retrograde motion thereof when released and thereby retain a portion of the web in a predetermined position relative to the support.

3. A device of the character described comprising, in combination, a support for a web, a roller engaging the web for feeding the same relative to the support, means for releasing the feeding means to permit retrograde motion of the web, and means adapted to engage the web to limit the retrograde motion thereof when released and thereby retain a portion of the web in a predetermined position relative to the support. 75

4. A device of the character described comprising, in combination, a support for a web, means for feeding the web relative to the support, and means for adjusting the position of a portion of the web relative to the support, the feeding means comprising a roller engaging the web at all times except during the adjusting operation, and the adjusting means comprising means adapted to engage the web to limit retrograde motion thereof during the adjusting operation. 85

5. A device of the character described comprising, in combination, a support for a web, means for feeding the web relative to the support, and means for adjusting the position of a portion of the web relative to the support, said feeding means comprising a pair of rollers engaging the web between them at all times except during the adjusting operation, and the adjusting means comprising means adapted to engage the web to limit retrograde motion thereof during the adjusting operation. 95

6. A device of the character described comprising, in combination, a support for a web, means for feeding a web relative to the support, comprising a pair of rollers engaging the web between them, means for relieving the web from restraint against retrograde motion, comprising means for separating the rollers, and means adapted to engage the web to limit the retrograde motion when relieved and thereby retain a portion of the web in predetermined position relative to the support. 100

7. A device of the character described comprising, in combination, a support for a web, means for adjusting the position of a portion of the web relative to the support, means for severing the web, and means for operating said severing means and said adjusting means simultaneously. 115

8. A device of the character described comprising, in combination, a support for a web, means for adjusting the position of a portion of the web relative to the support, means for severing the web, means for operating said severing means and said adjusting means simultaneously, and a reciprocating member on which the severing means and the adjusting means are mounted. 120

9. A device of the character described comprising, in combination, a support for a web, pins adapted to engage perforations in the web for adjusting the position of a por- 125

tion of the web relative to the support, a knife for severing the web, and a reciprocating member on which said pins and said knife are mounted.

- 5 10. A device of the character described comprising, in combination, a support for a web, a roller for feeding a web relative to the support, means for adjusting the position of a portion of the web relative to the support, comprising means for disengaging the roller from the web, means for severing the web, and means for operating said severing means and said adjusting means simultaneously.
- 15 11. A device of the character described comprising, in combination, a support for a web, a roller for feeding a web relative to the support, means for adjusting the position of a portion of the web relative to the support, comprising means for disengaging the roller from the web, pins for engaging perforations in the web to retain a portion thereof in predetermined position relative to the support, a knife for severing the web,

- 20 25 and a reciprocating member on which the knife, the pins and the roller-releasing means are mounted.

12. A device of the character described comprising, in combination, a support for webs, means for feeding a plurality of webs relative to the support, and means for adjusting the position of a portion of each of the webs relative to the support, the feeding means comprising a member for engaging the webs at all times except during the adjusting operation, and the adjusting means comprising means for limiting retrograde motion of the webs during adjustment.

13. A device of the character described comprising, in combination, a support for a plurality of webs, a pair of feeding rollers adapted to engage the webs between them for feeding the webs relative to the support, means for adjusting the position of all of said webs relative to said support, comprising means for relieving the webs from restraint against retrograde motion, and means for limiting the retrograde motion during adjustment.

40 45 50 55 60 14. In an autographic register, in combination, mechanism adapted to simultaneously feed a plurality of superposed apertured webs, and means adapted to adjust portions of said webs relative to each other comprising a controlling finger reciprocal across the paths of the webs adapted to enter the apertures in the superposed webs, and means adapted to hold said finger from longitudinal movement when in said apertures.

15. In an autographic register, in combination, mechanism adapted to simultaneously feed a plurality of superposed apertured webs, and means adapted to adjust portions of said webs relative to each

other comprising a controlling finger reciprocal across the paths of the webs adapted to enter the apertures in the superposed webs, and means adapted to hold said finger from longitudinal movement when in said apertures, said feed mechanism comprising co-operative feed rollers adapted to grip the webs.

16. In an autographic register, in combination, mechanism adapted to simultaneously feed a plurality of superposed apertured webs, means adapted to adjust portions of said webs relative to each other comprising a controlling finger reciprocal across the paths of the webs adapted to enter the apertures in the superposed webs, means adapted to hold said finger from longitudinal movement when in said apertures, said feed mechanism comprising co-operative feed rollers adapted to grip the webs, and means adapted to release said webs from the grip of said rollers, at will.

17. In an autographic register, in combination, mechanism adapted to simultaneously feed a plurality of superposed apertured webs, means adapted to adjust portions of said webs relative to each other longitudinally of the direction of feed, comprising a controlling finger reciprocal across the paths of the webs adapted to enter the apertures in the superposed webs, said feed mechanism comprising a roller adapted to rotate in the operation of feeding the webs, and means whereby the webs may be released from the pull of said roller to permit longitudinal adjustment to be effected by said finger.

18. In an autographic register, in combination, mechanism adapted to simultaneously feed a plurality of superposed apertured webs, means adapted to adjust portions of said webs relative to each other, longitudinally of the direction of feed comprising a controlling finger reciprocal across the paths of the webs adapted to enter the apertures in the superposed webs, said feed mechanism comprising a roller adapted to rotate in the operation of feeding the webs, and means whereby the webs may be released from the pull of said roller to permit said longitudinal adjustment to be effected by said finger, said finger being independent of said roller.

19. In an autographic register, in combination, mechanism adapted to simultaneously feed a plurality of superposed apertured webs, means adapted to adjust portions of said webs relative to each other longitudinally of the direction of feed comprising a controlling finger movable into and out of apertures in the superposed webs transversely of the plane of the webs, said feed mechanism comprising a roller adapted to rotate in the operation of feeding the webs, and means whereby the webs may

be released from the pull of said roller to permit said longitudinal adjustment to be effected by said finger.

20. In a friction-roll manifolder employing perforated form strips, a drive roll and a co-operative pressure roll for feeding said strips, means for relaxing the pressure between the rolls after feeding said strips a predetermined distance, and form adjusting means for engaging form perforations at the time of said pressure relaxation.

21. In a machine of the character described, the combination of suitable feeding means, and suitable registering means adapted to relatively shift superposed webs into registered position, with means for releasing the feeding means from the webs, means for severing slips from the webs, and means for simultaneously operating said severing means and releasing said feeding means from the webs.

22. In a machine of the character de-

scribed, the combination of suitable web feeding means, operating means therefor to effect a predetermined length of feed, means 25 for severing a slip from the web, suitable registering means adapted to correct the position of the web and means for simultaneously operating said severing means and said registering means and releasing 30 said feeding means from the web.

23. In a machine of the character described, the combination of suitable web feeding means, a web-cutting device and a web registering device, said cutting device 35 being arranged to release the feeding means from the web and actuate said registering device.

In testimony whereof I affix my signature, in the presence of two witnesses.

LOUIS F. HAGEMANN.

Witnesses:

P. V. KELLER,
W. H. HOUSTON.
